Patented 11th Sept. 1847.

HOT AIR & AIR TIGHT

Fig. 2.

Wes. 148

James H. Conklin   Peekskill New York
Letters Patent (Design No 148) Dated 11th Sept 1847.

The schedule referred to in these Letters Patent and making part of the same.

To all whom it may concern: Be it known that I, James H. Conklin, of the village of Peekskill, in the County of Westchester, and State of New York, have invented a new design for a cook stove, which is described as follows, reference being had to the annexed drawings of the same, making part of this specification.

Figure 1 is a plan of the front plate forming part of the design the door being removed. Figure 2 is a plan of the side plate the oven door being removed.

Figure 3 represents one of the ornamental covers.

The design consists of a raised entablature A, at the upper edges of the plates, supported by the half columns B, or columns in alto relief, ornamented by leaves, fillets and flutes of the design represented at B in figures 1 and 3, resting upon pyramidal bases, upon the bottom plate of the stove, the entablature being ornamented with raised letters, signifying various words such as HOT AIR & AIR TIGHT STOVE.

The front plate, is further ornamented by a raised segment pannel C, flowered around the inner edge of the pannel and ornamented by the letters, ^{inclosing words THE} PARAGON.

This plate is further ornamented by another raised and flowered pannel D, near the bottom containing the raised letters indicating words, that spell the names of the manufacturers WHITNEY & MONTANYA

The outside of the side plates, against the fire chamber are ornamented by raised pannel work E, containing a flower F in high relief in the centre such as that represented at F figure 2

The circular covers G, are ornamented with a design of a flower in the centre, surrounded by a circle of leaves - a circular channel -

3

Des. 1478

and a circular rib as represented at G fig. 3.

What I claim as my invention and desire to secure by Letters Patent is the production of the new patterns, for stone plates as described in the specification, and represented in the drawings at figures 1 & 2 & 3.
